UNITED STATES PATENT OFFICE

OSCAR A. TURNER, OF CHICAGO, ILLINOIS

DRAFTING INSTRUMENT

Application filed March 5, 1928. Serial No. 259,022.

My invention relates to drafting instruments, and has for its object the production of an instrument which co-operates with a plane surface and suitable pivots to produce 5 curves which serve to solve mathematical problems, and other curves useful in the production of ornamental figures.

In the accompanying drawings

Fig. 1 shows the instrument in the form 10 of a carpenter's square, and provided with graduations and tracing points by which a variety of curves may be drawn;

Fig. 2 shows a diagram produced by the instrument, which diagram serves for the 15 geometrical trisection of an angle by plane geometry; and

Fig. 3 shows the main part of the device in the form of a draftsman's triangle provided with graduations on two legs, and also 20 provided with a plurality of tracing points, some at least of which points have definite relationships to the graduations.

In Fig. 1, the body 10 has an interior right angle at 11 and an exterior right angle at 12. 25 The legs 13 and 14 may be of any length. Along the inside of leg 13 are graduations marked "1," "2," "3," etc., and similar graduations may or may not be along the leg 14.

The graduations begin at the corner 11, but 30 may be along the outer edge, and may begin at any desired point.

In the leg 14, and in a line which is an extension of the inner edge of leg 13, are small holes 15, 16, and 17. In leg 13, and in line 35 with the inner edge of leg 14, are other holes 18 and 19. The distance of the hole 19 from the corner 11 is the same as the distance of the graduation marked "1" from the same corner. In other words, the hole 19 is a unit 40 distance from corner 11, and in a direction perpendicular to the line of the inner edge of leg 13.

Exactness for this particular point is given 45 because it, in conjunction with two pivoting points which are twice the unit distance from each other, and the inner edges of the legs 13 and 14, serves to trace a curve which I call a "trilocus," which curve is part of a general diagram which I call a "trisectroid."

50 An illustration of the operation of the ap-

paratus by the curve drawn from this point will serve to show how said apparatus is used for various purposes. I have chosen this particular point for illustration because the trisectroid serves for a simple solution 55 of the trisection of an angle.

Referring to Fig. 2, from the center O, and with unity (the distance from 11 to 19) as a radius, draw the semi-circle ADB. At the extremities of the diameter A—B, stick pins 60 which will form pivots. These pins may be common pins ordinarily sold in stores, and are here assumed to be without sensible diameter. Then apply the body 10 to these pivots as shown in dotted lines.

If the body 10 is moved rotatively with its lower face against the surface on which the circle is drawn, and its interior edges are kept in contact with the pins A and B, then the point 11 will trace out the semi-circle ADB. 70 This is because of the fact that the angle 11 is a right angle, and the fact that any angle, as ADB, inscribed within a semi-circumference is a right angle. If a marker, as a pencil point, be inserted thru the hole 19 at the 75 time the body 10 is moved as described, then the marker will trace the curve 19CE, which is the trilocus.

From O as a center, draw the line OC so 80 that the angle BOC is the angle to be trisected. From the point where the line OC cuts the trilocus, draw the line AC, then the angle ACO will be one-third of the angle BOC.

To prove this, from the point D, where the 85 line AC cuts the circle, draw the line DO, which is a radius of the circle. But the line DC is equal to a radius by construction, as it is the distance of the point 19 from the angle 11 of the instrument. As a consequence, the triangle CDO is an isosceles triangle with the angle at O equal to the angle at C.

If we call the angle at C unity or 1° , then 90 the exterior angle ADO will be the sum of the angles at C and O, or 2° . In the triangle OAD, the side OA and side OD are radii, and the angles at O and D are equal to each other, that is, each one is equal to 2° . The exterior angle DOB is equal to the sum of the interior angles at A and D, that is, it is equal to 4° . 100

But as the angle DOC equals 1°, COB must equal 3°.

The instrument shown in Fig. 3 has graduations in inches along one leg and graduations in the metric scale along the other leg.

5 The instrument is shown as a draftsman's triangle with various tracing points. It may, however, be made in other forms. The essentials are that it must be movable with respect to two pivots, and a fixed point in the instrument must travel in the arc of a circle while being so moved. Also, that there must be some other point on the instrument which may be used to trace another curve which will

10 have a definite relationship to the arc traced.

15

I have used the term "rays" to designate those lines which go outward from the ends of the diameter A—B and cut the curve CE. It is to be noted that the part of a ray between

20 the circle and the curve is a fixed quantity for any particular curve. In Fig. 2, this distance is the radius of the circle. If the tracing had been thru any one of the holes 15, 16, 17 or 18, the distance between the circle and the curve

25 would have been the distance of the hole from the corner 11.

What I claim is:

In a device of the class described, a body having straight edges furnishing an interior

30 right angle, said body having graduations along one edge beginning at the apex of said angle, and said body having a small hole adapted to receive a tracing point, said hole being located in a line which is an extension

35 of the straight edge of the other leg and at a distance from said apex which is a multiple of the distance of the first graduation from said apex.

OSCAR A. TURNER.
